UNITED STATES PATENT OFFICE

FRANK B. CALDWELL, OF OAK PARK, ILLINOIS, ASSIGNOR TO LINK-BELT COMPANY, OF CHICAGO, ILLINOIS, A CORPORATION OF ILLINOIS

PIVOTED EXTERNAL COUNTERWEIGHT

Application filed March 4, 1927. Serial No. 172,596.

My invention relates to improvements in car unloaders and has for one object to provide a new and improved form of car holding clamp which holds the car in the cradle during the dumping operation. Another object is to provide a form of car holding clamp wherein the weights adapted to hold the car on the cradle are located and supported at a point removed from the cradle thereby making it possible to remove the weight from the cradle, thus providing a cheaper structure and one which can be more easily obtained. Other objects will appear from time to time throughout the specification and claims.

My invention is illustrated more or less diagrammatically in the accompanying drawings, wherein—

Figure 1 is a side elevation with parts in section;

Figure 2 is a section along the line 2—2 of Figure 1;

Figure 3 is a section similar to Figure 2 except that the parts are shown after the car has reached substantially the dumping position;

Figure 4 is a section along the line 4—4 of Figure 3.

Like parts are indicated by like characters throughout the specification and drawings.

A is a concrete or other suitable construction upon which the structure may be erected. A¹ is the hopper into which the car is to be dumped. A² A² are pillow blocks mounted on the foundation, tied together by the rods A³. Pivoted on these pillow blocks are equalizing levers A⁴. At each end of the equalizing lever is a roller A⁵ A⁵. There may be a plurality of these pairs of equalizing levers spaced along the foundation; preferably I provide, however, one pair at either end so that the car unloader is supported only at its two ends upon the four rollers carried by the pair of equalizing levers. A⁶ is a car dumping cradle. It comprises a bridge or girder structure A⁷ terminating at either end in a roller ring A⁸. It is these roller rings that rest upon the rollers A⁵ A⁵ to permit rotation of the

cradle. A⁹ is a turning cable. There are two of these cables, each cable is anchored at each end on a roller ring by means of a sliding rod A¹⁰ traveling in a trunnion block A¹¹, which block is pivoted in ears A¹². A spring A¹³ is interposed between the far end of the trunnion block and an adjusting nut A¹⁴ on the end of the rod A¹⁰. This cable is wound about a driving drum A¹⁵ and since it is dead ended on the roller ring, rotation of the driving drum forward or backward as the case may be will cause rotation of the cradle, the cable wrapping and unwrapping itself from about the face of the roller ring, the springs cushioning the shock of stopping and starting.

The drums A¹⁵ are mounted upon the driving shaft A¹⁶ rotatable in the bearing brackets A¹⁷ adapted to be driven through any suitable source applied to a gear A¹⁸.

It will be noted that in order to compensate for a longitudinal variation in foundation and cradle, that the rollers at one end of the cradle are slotted to engage the bearing ring A¹⁹ but smooth at the other end so that the cradle is anchored by the engagement of the slotted roller at one end free to expand and contract at the other.

Carried by the lower portion of the cradle are a plurality of transverse tracks B. On them travel transfer rollers B¹, which rollers carry the laterally movable transfer table B². Railroad tracks B³ extend longitudinally on this transfer table along the length of the cradle and the car B⁴ as indicated may travel along these tracks into dumping position on the cradle. It will be noted that the cradle is generally U-shaped in cross section to support the car. There is a pad B⁵ at one side of the cradle so that as the cradle rotates in a counter clockwise direction from the position shown in Figure 1, the transfer table as it travels to the left will permit the car to be brought to rest against the pad B⁵, assuming with respect to the cradle the position shown in Figure 3. The means for controlling this movement of the transfer table during operation form no part of my present invention and I therefore have not disclosed or illustrated them here.

There are a plurality of clamps provided to hold the car in place in the cradle when in the dumping position. They are similar, however, and a description of one set of clamps will suffice for all because there are 5 separate manipulating and holding means for each pair, which means are with some exceptions to all intents and purposes independent one of the other.

10 C⁴ are clamp guides arranged in opposed pairs on opposite sides of the cradle extending vertically above the cars. C² C³ are car holding clamps adapted to engage the upper edge of the car and hold it in the cradle. The clamp C² has a comparatively slight overhang because the movement of the transfer table brings the car over against the pad B⁸ beneath the overhang of the clamp C². Since cars, however, are of different widths, the clamp C³ has a very considerable overhang so that no matter how narrow the car, that clamp will always be able to reach and engage it.

In the position shown in Figure 2, the 25 clamps are raised above the car to the maximum elevation to permit cars of maximum height as well as lower ones to enter the structure. The clamp raising system comprises cables C⁴ C⁵ dead ended on the lower 30 end of the clamps C² C³ respectively passing over sheaves C⁶ adjacent the clamp guides, the cable C⁵ passing down over an idler sheave C⁷ thence across the structure to the sheave C⁸, the cable C⁴ passing directly 35 around that sheave, thence the two cables pass back around the structure over an idler sheave C⁹ down through the foundation to a clamp raising counterweight C¹⁰. In the position shown, this clamp raising counterweight has come to a full stop against the underside of the concrete foundation and therefore the clamps are positively lifted as a result of the rotational movement, the 40 position of the parts being such that the distance in this case between the sheave C⁹ and the sheaves C⁸ and C⁷ around the sheave C⁸ is a maximum. Referring now to Figure 3, in the dumping position, the distance 45 between the sheave C⁹ and the sheaves C⁸ and C⁷ is greatly reduced. In fact, the sheave C⁸ is now altogether out of contact with the cable C⁴ and barely touches the cable C⁵. These two cables riding around the pulley C¹¹ equalize with respect to the 50 counterweight C¹⁰ so as to exert an equal tension on the two clamps at all times. The clamps having been lowered to engage the car, the clamp raising counterweight C¹⁰ is now out of contact with the foundation and hangs freely, exerting on the cables C⁴ C⁵ only that tension resultant from its 55 weight.

Referring now to the clamp holding system, D is a cable dead ended at one end on the clamp C³ passing down around the

sheave D¹ in line with the travel of the clamp, thence about a sheave D² adjacent the periphery of the roller ring, thence about a sheave D³ on the carriage track D⁴, thence about a sheave D⁵ on the carriage D⁶ back 70 about another sheave D³ concentric with the first going around it in the opposite direction and thence travels along the sheaves D⁷ D⁸ D⁹ D¹⁰ D¹¹ D¹², which sheaves are arranged on a generally spiral line with the sheave D⁵. Out adjacent the periphery of the roller rings with the sheave D¹² spaced inside such periphery, the cable extends down over a sheave D¹³ and up in line with the travel of the clamp to the clamp C² 75 where it is dead ended.

The carriage D⁶ is provided with rollers E adapted to roll along the track D⁴. E¹ is a cable dead ended on the carriage D⁶ and wound about the small drum E². This small drum is rigidly mounted on the shaft E³ in pillow blocks E⁴. E⁵ is a large drum rigidly mounted on the shaft E³. Dead ended and wound about it is a cable E⁶ which cable extends down and terminates at the holding 80 counterweight E⁷. E⁸ is a ratchet wheel mounted for rotation with the shaft E⁸. E⁹ is a counterweighted lever pivotally mounted on the shaft E³. E¹⁰ is a dog pivoted on the lever E⁹ and adapted under some conditions 85 to engage the ratchet E⁸.

The spring F interposed between a stirrup F¹ and the tail of the dog E¹⁰ tends normally to hold the dog in engagement with the ratchet. F² is a bell crank lever pivoted on the foundation engaging the tail of the dog and adapted to compress the spring and hold the dog out of engagement with the ratchet. F³ is a thrust rod terminating at a lever F⁴ on the shaft F⁵, which lever is associated with a counterweighted lever F⁶, the weight of the counterweight tending to hold the bell crank lever in the position shown in Figure 2 whereby the pendulum or counterweighted lever E⁹ is free to rotate on the shaft without reference to the ratchet. F⁷ is a cam roller on the opposed end of the lever F⁶. This roller projects outwardly toward the periphery of the roller ring into the path of the cam F⁸. In the position shown in Figure 2 the counterweighted lever is disconnected. In the position shown in Figure 3, the cam F⁸ has forced the lever F⁶ into the opposite position retracting the bell crank lever F², permitting the spring to cause the dog to engage the ratchet and we now find that the counterweighted lever E⁹ is locked on the shaft E³ and further rotation of the cradle exerting a tension on the cable D causes rotation of the lever E⁹ and raises the counterweight E⁷. 100

It will be noted that in the position shown in Figure 2, the counterweight E⁷ is at this upper position. The counterweighted lever E⁹ hangs freely. As the cradle rotates the 105 110 115 120 125 130

sheave D^2 recedes from the sheave D^3 . The cable D as it extends around the sheaves D^7 D^8 D^9 D^{10} D^{11} D^{12} is shortened as it passes off the sheave D^3 in a clockwise direction and is lengthened somewhat as it passes off the D^5 in a counter clockwise direction, the ultimate result being to first move the sheave D^5 on the carriage D^6 toward the right paying out on the counterweight E^7 and later to move it toward the left again lifting up on the counterweight E^7 and also on the counterweighted lever so that the weight of the car in the dumping position is carried both by the counterweight E^7 , the counterweight E^7 working through the differential drums E^5 E^2 and the counterweighted lever E^9 exerting its force through the long lever arm.

It will be noted that there are only two counterweighted levers F^6 and that the shaft F^5 along the entire length of the cradle controls the dog for each of the two counterweighted levers associated one with each of the clamps.

While I have shown the sheave D^5 traveling with a carriage, having rollers and the like, it will be understood that by the language "carriage" I do not mean any particular kind of carriage and the sheave itself might be held in position merely by the supporting cables and serve as its own carriage without departing from the spirit of my invention.

The use and operation of my invention are as follows:

With the parts shown in the position shown in Figure 2 the car is run onto the transfer table, the motor or other drive is then started and the cradle is rotated in a counter clockwise direction. This rotation tends to pay out on the clamp lifting cables C^4 C^5 permitting the clamps to descend to engage the top of the car. At the same time and before the clamps have actually come into engagement with the car, the transfer table will have to move toward the left to bring the car side into engagement with the side wall of the cradle. The lowering of the clamps will cause a paying out of the car holding counterweight E^7 until when the parts are in the position shown in full lines in Figure 3 the car holding clamp counterweight will have come down a considerable distance beneath the foundation. During this time until the dumper has rotated through an angle of approximately ninety degrees, the only holding power exerted by the clamps is supplied by the counterweight E^7 and the weight of the clamps themselves. At a certain predetermined angle when the cam F^8 comes into operation the counterweighted lever is engaged with the differential drum shaft. At this point in the rotation, the compensated effect is diminished so that there is a tendency to move the carriage D^6 to the left. This

movement raises the counterweight E^7 and also the counterweighted lever E^9 is rotated in a counter clockwise direction from the vertical position when the car dumper has been rotated through an angle of approximately ninety degrees to a substantially horizontal position when the car is at the forty-five degree angle of dump. Thus when the car is at its furthest excursion and the load on the holding system is greatest the counterweighted lever is at approximately the horizontal position and in a position where it can exert its maximum effect. Upon the return movement of the dumper the reverse of these operations take place.

I claim:

1. A car dumper comprising a rotatable cradle, car holding clamps and means for operating them comprising a movable carriage, a positive connection between the carriage and the clamps, means for displacing the carriage to take up slack in the connection, and separate means associated with the carriage for holding it to support a car while in the dumping position, a track along which the carriage travels, the track and carriage being removed from the cradle.

2. A car dumper comprising a rotatable cradle, car holding clamps and means for operating them comprising a movable carriage, a positive connection between the carriage and the clamps, means for displacing the carriage to take up slack in the connection and separate means associated with the carriage for holding it to support a car while in the dumping position, the carriage holding means comprising a drum, a cable wound about the drum and dead ended on the carriage, a counterweighted lever mounted for rotation about an axis concentric with the drum and means controlled by the cradle and operative after the cradle has rotated a predetermined amount for connecting the lever and the drum so that movement of the cradle responsive to the tension on the clamp and cable will be resisted by the counterweighted lever.

3. A car dumper comprising a rotatable cradle, car holding clamps and means for operating them comprising a counterweight, a sheave removed from the cradle and sheaves on the cradle, a cable extending from the counterweight over said sheaves to the clamps whereby rotation of the cradle toward the car dumping position decreases the distance between one of the sheaves on the cradle and the sheave removed from the cradle to pay out the counterweight and permit the clamps to lower toward a car and a stop removed from the counterweight whereby as the cradle rotates away from the dumping position the counterweight is brought into engagement with the stop and positively raises the clamps, and a movable carriage, a positive connection between it

and the clamps, yielding means for displacing the carriage to take up the slack in the connection as the clamps are drawn down toward the car and means for holding the carriage to support a car when in the dumping position.

4. A car dumper comprising a cradle and means for rotating it, car holding clamps movable thereon toward and from a car, a rotatable drum removed from the cradle, cables connecting the drum and the clamps, means for rotating the drum to exert a tension on the cables and take up the slack thereof independent of the position of the clamps, a counterweighted lever associated with the drum and means responsive to rotation of the cradle for connecting the lever and drum whereby as the cradle rotates to the dumping position the counterweighted lever resists rotation of the drum and exerts a car holding tension on the cable.

5. A car dumper comprising a cradle and means for rotating it, car holding clamps movable thereon toward and from a car, a rotatable drum removed from the cradle, a clamp holding cable associated with the drum, means for maintaining a tension on the cable between the drum and clamp to take up the slack, a counterweighted lever associated with the drum and means automatically responsive to the rotation of the cradle for disconnecting the drum and counterweighted lever while the cradle is in the generally upright position for connecting the drum and counterweighted lever when the cradle approaches the dumping position to cause the counterweight lever to rotate the drum to exert a clamp holding tension on the cable.

6. Signed at Chicago, county of Cook, and State of Illinois, this first day of March, 1927.

FRANK B. CALDWELL.
